PARKING CANOPY

John Selby, 1350 Ghent Hill Road, Akron, Ohio

Filed Mar. 17, 1960, Ser. No. 59,778

Term of patent 14 years

(Cl. D13—1)

FIG. 1

FIG. 4

FIG. 5

FIG. 2

Figure 1 is a view in perspective of a parking canopy for double parking embodying my design;

The dominant features of my design reside in the portions shown in full lines.

I claim:

The ornamental design for a parking canopy, as shown and described.
